UNITED STATES PATENT OFFICE.

NEIL E. SALSICH, OF BETHLEHEM, PENNSYLVANIA.

GAUGE ROD.

Application filed August 4, 1925. Serial No. 48,041.

My invention relates to gauge rods or rail braces and particularly to gauge rods of the insulated type.

It is customary in railroad track construction, when gauge rods are used, to insulate the rails in such a manner as to prevent interference with the electric signaling circuits. To effect such insulation, fibre bushings have been inserted between the rods 5 and the movable clip members. As bushings of this character are exposed to changing weather conditions and are subjected to severe shocks, it has been found difficult to manufacture fibre in the cylindrical form required in the above described construction which will withstand the service conditions 10 in a durable and satisfactory manner.

It is known that fibre, manufactured in the form of sheets, is very durable and sheet 20 fibre has been suggested as an insulator in a gauge rod construction, such an insulator being placed intermediate to the rail and the clip member. In this latter arrangement the fibre insulator is subjected to severe lateral 25 forces in a direction longitudinally of the rail occasioned by the tendency of the latter to creep under traffic.

Accordingly, therefore, the principal object of my invention is to provide an insulated gauge rod construction having an insulator member formed of sheet insulating material and to connect such an insulator to its clip to prevent lateral displacement.

Another object of my invention is to provide 35 an insulator gauge rod construction wherein a portion of the thrust, due to the clamping action, is taken against the vertical web of the rail.

Apparatus made in accordance with my 40 invention is illustrated in the accompanying drawings, forming a part of this application, in which:

Fig. 1 is a side elevation of a gauge rod showing the construction embodying my invention;

Fig. 2 is an end view of the clip showing the insulator member in position;

Fig. 3 is a sectional view of a modified form of my invention;

Fig. 4 is a cross section taken on line IV—IV of Fig. 3;

Fig. 5 is a cross section taken on line V—V of Fig. 4; and

Fig. 6 is a partial plan view of the gauge 55 rod shown in Fig. 1.

Referring now to the drawings more in

detail for a better understanding of my invention, I show a gauge rod 10 having a fixed jaw 11 at one end for engagement over the outside flange of one rail of a track. The 60 other end of the rod 10 is threaded, at 12. A movable jaw or clip 13 fits over the threaded end and nut means 14 engages the threaded portion 12 in order to force the movable clip 13 inwardly to engage the latter over the 65 outside flange of the other rail of the track.

The movable clip 13 comprises a sleeve portion 15 which fits freely about the rod 10 and which has an upper plane bearing surface 16 adapted to engage beneath the bottom face of the rail. At its outer end, the movable clip member is provided with an overhanging portion 17 adapted to engage over the outside flange of a rail and the portion 17 is continued upwardly and inwardly 70 to form a rail web abutment 18. The overhanging portion 17 preferably defines, with the flat surface 16, a clearance space 19 whereby it is assured that the overhanging member 17 may firmly engage over the top 75 surfaces of rail flanges of variable widths and thicknesses.

The movable clip member 13 is preferably made of malleable cast iron and it is provided with ribs 20 for strengthening purposes.

An insulator member 21, made from any suitable type of flat insulating material, is shaped to conform to the upper surface 16 of the movable clip and to the inside surfaces 90 of the overhanging and abutment portions 17 and 18, respectively.

Lateral displacement of the insulator member 21 is preferably prevented by having the bent or angular portion 22 thereof 95 extend into a pocket 23 provided in the clip, the pocket having end walls 24 which engage over the angular portion 22 of the insulator member laterally to prevent relative lateral displacement of the insulator 100 member with respect to the clip. As illustrated, the insulator member 21 is preferably made wider than the base portion of the clip so as to assure that the insulator member shall overlap the edges of the base member, as shown in Fig. 4; and, in order to accommodate the relatively wider insulator member, the outer end portion of the movable clip is widened laterally, not only for this purpose, but also to provide sufficient material for the pocket 23 and for the outside overlapping or flange portions 24.

The base portion of the movable clip preferably extends inwardly beyond the inside edge of a rail in order that the insulator member 21 may extend inwardly beyond the 5 base of the rail so that such insulator member may be fastened, for example, as by riveting, beyond the inner edge of the rail, such fastening means being indicated at 25, for the purpose of positively securing the 10 insulator member to the clip at the inner side of a rail while at the same time preserving the insulating characteristics.

In Fig. 3, I show another way of fastening the inner end of the insulator strip 21. Here 15 the inner end 26 of the strip is bent down and perforated at 27 for the rod 10 in order that the rod may hold the inner end of the strip against lateral displacement.

From the foregoing, it will be apparent 20 that I have devised an insulating type of gauge rod clip in which the insulator is simple in design and which design lends itself to the production of a durable construction and one in which the insulator member is 25 held positively in position against lateral creepage.

While I have shown my invention in but 30 one form, it will be obvious to those skilled in the art that it is not so limited, but is susceptible of various other changes and modifications without departing from the spirit thereof, and I desire, therefore, that only such limitations shall be placed thereupon as are imposed by the prior art or as 35 are specifically set forth in the appended claims.

Having thus described my invention, what 40 I claim as new and desire to secure by Letters Patent is:

1. In a gauge rod construction, the combination of a rod member having a threaded end, a clip movable longitudinally of the rod and having a seat portion shaped to engage a flange portion of a track rail, nut 45 means engaging the threaded end portion of the rod for causing said clip to move inwardly to engage the track rail, an insulator member shaped to conform with the general configuration of said seat portion of the clip 50 and adapted to be interposed between the latter and the track rail, and an abutment member projecting from the movable clip and adapted to engage the insulator member so as to prevent lateral movement thereof 55 with respect to the clip member.

2. In a gauge rod construction, the combination of a rod member having a fixed clip at one end and having its other end threaded, a movable clip loosely mounted on the rod, nut means engaging the threaded rod end outside of the movable clip, said movable clip having a seat portion adapted to overhang the upper face of the flange of a track rail and to extend beneath the bottom 60 face of said flange, an insulator member of

substantially uniform cross section and shaped longitudinally to conform with the general configuration of the seat portion of the movable clip, and an abutment member 70 projecting from the movable clip and adapted to engage the insulator member so as to prevent lateral movement thereof, with respect to the last mentioned clip member, when the gauge rod is clamped in position on the track rails.

3. In a gauge rod construction, the combination of a rod member having a fixed clip at one end and having its other end threaded, a movable clip loosely mounted on the rod, nut means engaging the threaded rod end outside of the movable clip, said movable clip having a seat portion disposed beneath the base of a rail, over the outside flange of the latter, and contiguously to the web thereof, an insulator member of substantially uniform cross section and shaped longitudinally to conform with the general configuration of the seat portion of the movable clip and an abutment member projecting inwardly from the movable clip, and adapted to engage the insulator member so as to prevent lateral movement thereof with respect to the last mentioned clip member when the gauge rod is clamped in position on the track rails.

4. In a gauge rod construction, the combination of a rod member having a fixed clip at one end, a movable clip mounted on the rod in opposed relation to the fixed clip, means engaging said rod and adapted to cause the clips to move toward each other, each of said clips having hook portions adapted to engage over the flanges of a track rail, an insulator member of substantially uniform cross section and shaped longitudinally to conform with the general configuration of the rail engaging surface of one of the hook portions, and an abutment member projecting inwardly from the last mentioned clip member and adapted to engage the insulator member so as to prevent relative lateral movement thereof when the gauge rod is clamped in position on the track rails.

5. In a railway track construction, the combination with a pair of track rails, of a gauge rod comprising a rod member having a fixed clip at one end, a movable clip mounted on the rod in opposed relation to the fixed clip, means engaging the rod member and operable to cause the clips to move toward each other and clamp the rails, an insulator member interposed between one of the clip members and its rail, and an abutment member projecting from the last-mentioned clip member and engaging the insulator member to positively prevent the relative displacement thereof.

6. In a railway track construction, the combination with a pair of track rails, of a gauge rod comprising a rod member hav-

- ing a fixed clip at one end, a movable clip mounted on the rod in opposed relation to the fixed clip, means engaging the rod member and operable to cause the clips to grip the outside flanges of the track rails, an insulator member interposed between one of the clip members and the contiguous surfaces of a rail, and abutment members projecting inwardly from the last-mentioned clip member and engaging the insulator member laterally to positively prevent lateral movement thereof with respect to the clip member.
7. In a railway track construction, the combination with a pair of track rails, of a gauge rod comprising a pair of clip members engaging over the outside flanges of the track rails, a rod member connecting said clip members, an insulator member interposed between one of the clip members and a rail, and means projecting from the latter clip member and engaging said insulator member to prevent positively relative movement between the insulator member and its clip member.
8. In a railway track construction, the combination with a pair of track rails, of a gauge rod comprising a pair of clip members in opposed relation and engaging over the outside flanges of the track rails, a rod member connecting said clip members, one of said clip members extending inwardly beyond the inner edge of the flange rail and also extending inwardly and upwardly into contiguity with the outside face of the web of said rail, an insulator member interposed between the last mentioned clip member and the rail, and means to positively prevent lateral movement of the insulator member with respect to the clip member.
9. The combination with a pair of track rails, of a gauge rod structure comprising a pair of clip members in opposed relation and engaging over the outside flanges of the track rails, a rod member connecting said clip members, an insulator member interposed between one of the clip members and the rail, said insulator member and the last mentioned clip member extending beyond the inner edge of the rail, and means disposed beyond the rail to fasten the latter members in fixed relation with respect to one another.
10. In a gauge rod construction, the combination of a rod member having a fixed clip at one end, a movable clip loosely fitting over the other end of the rod member, means for causing the movable clip to move toward the fixed clip in order that the clips may grip outside flanges of the rails of a track, the movable clip including a base portion having a flat upper surface disposed beneath the base of a rail and extending beyond the inner edge of the inner flange of the latter and having an outer portion which overhangs the outer flange of a rail, said overhanging and base portions forming a pocket provided with end walls at the junctions thereof, an insulator member interposed between the rail and the base and overhanging portions and having a bent or angular portion disposed in said pocket and one end of the insulator member extending beyond the inner edge of the rail, and means for securing the inner end of the insulator member to the base member beyond the inner edge of the base of the rail.

In testimony whereof I hereunto affix my signature this 22nd day of July, 1925.

NEIL E. SALISCH.
